BALLAST STRUCTURE FOR FLUORESCENT LAMPS

Albert E. Feinberg and Paul Berger, Chicago, Ill., assignors to Advance Transformer Co., Chicago, Ill., a corporation of Illinois

Filed Oct. 1, 1962, Ser. No. 227,469

8 Claims. (Cl. 315—187)

This invention relates generally to a ballast structure for gaseous discharge devices and more particularly, is concerned with the construction of a ballast in which laminations which form the core are made with a minimum of scrap. The invention is also concerned with a novel ballast for gaseous discharge devices including a transformer which has a secondary winding intended to carry a leading current.

The word "ballast" has come to signify in this art a structure which performs several functions, including in addition to ballasting, raising line voltage to ignition voltage by transformation and the automatic lowering of the voltage after ignition to operating value.

All gaseous discharge devices require a higher voltage for igniting the same than for operating the same, and once ignited, the impedance of the device decreases to such a radical extent that unless in some way prevented from doing so, the device will destroy itself. The ballasting provides this deterrent.

It is well known in this art that a high leakage reactance transformer will perform all of the desired functions mentioned above. The high leakage reactance transformer is one in which at least a principal secondary winding is loosely coupled relative to the primary winding so that although the benefits of transformation in accordance with turns ratio are available on open circuit, as soon as current flows through the circuit, the high leakage reactance impedes the flow of current lowering the voltage across the load.

The ballast which will be described hereinafter and which comprises the invention herein, is one which is intended for use with fluorescent lighting lamps of the so-called "rapid-start" variety. These lamps have filaments in their envelope ends which are continuously energized and consequently a ballast must also serve the function of providing current continuously to these filaments. The ballast of the invention is constructed to provide such filament windings.

Rapid-start fluorescent lamps are normally operated in pairs, each pair being served by a single ballast. The circuit of the arrangement is such that on open circuit full output voltage of the ballast is applied to one of the lamps because of a by-pass or shunt circuit across the second lamp. Upon ignition of the first lamp, the current flows through the shunting circuit of the second lamp and produces a voltage in a condenser in the shunt which raises the voltage across the lamp to such an extent that the second lamp thereafter ignites. Current then flows in series through both of the lamps and the ballast windings. In order to provide good power factor in the ballast as a whole, a power factor correcting condenser is included in series with the lamps. This causes a leading current to flow in the principal secondary winding of the ballast.

As described in U.S. Patent No. 2,461,957, core saturation and resulting wave shape distortion will occur in the current flowing through the lamps unless one places a bridged gap in the magnetic circuit in the vicinity of the secondary winding which carries the leading current.

Attention is also invited to U.S. Patent No. 2,892,249 which describes a method of manufacturing a transformer core. It is contemplated that the ballast of the invention herein will be manufactured in accordance with the teachings of the said U.S. Patent No. 2,892,249.

2

A structure has been devised heretofore by one of the applicants herein in which the teaching of the said Patent 2,892,249 were applied to the manufacture of a transformer core for a ballast connected into a rapid-start circuit and in which the principles of the said U.S. Patent No. 2,461,957 were used to prevent saturation of the core in the vicinity of the secondary winding which carries the leading current. The said Patent 2,892,249 teaches the use of scrapless laminations of the so-called T and F configuration punched matingly from strips of steel and thereafter rearranged to form the necessary windows for the windings of the ballast. This will be brought out in more detail hereinafter and reference may be had to the said patent for additional information.

10 The center projection of the F-shaped laminations, in accordance with the teachings of the said Patent 2,892,249, are punched into the side edges of the elongate portion of the T-shaped laminations so that when rearranged to form the core, the center winding leg has notches and the side legs have inward protrusions. Proper adjustment of the length of the inward protrusions provides the gaps for the shunt. By proper choice of dimension, the notches in the center winding leg will be located on the interior of the secondary winding and thereby provide a bridged gap in the center core giving the benefits of increased efficiency, good lighting characteristics, etc.

This invention relates specifically to an improvement on the last described structure.

The position of the bridge gap in the T-shaped lamination, that is in the center winding leg, was determined in the previous structure by the provision of the shunt and the relative dimensions required in the windows produced to accommodate the primary and secondary windings.

30 Heretofore it was believed that the dimensions of the resulting transformer core were more or less limited because the distance between the resulting shunt and the bridged gap controlled to a great extent the characteristics of the ballast. Attempts made to decrease the size and weight of the core, or to cut down on the amount of copper wire were not successful. Problems arose in heating, wave shape distortion and the ballast was more expensive.

35 As an important example, the structure above referred to which was devised for two 40-watt rapid-start fluorescent lamps was a ballast having a transformer core formed of laminations $4\frac{1}{4}$ inches long and a little over 2 inches wide stacked .8 inch high. The width of the center winding leg was somewhat more than $\frac{3}{4}$ of an inch, the width of the side legs was a little more than $\frac{1}{3}$ of an inch, the width of the bridging portions and hence the distance 40 which the F-shaped parts and T-shaped parts moved lengthwise from their original nested positions was .385 inch.

45 As a result of the invention herein, it was possible to decrease the length of the core by one-half inch, decrease the number of turns of wire, and hence cut down on the size, weight and cost of the ballast without loss of lighting efficiency. A complete comparison of dimensions will be set forth in describing the specific example of the invention hereinafter.

50 55 60 The primary object of the invention is to provide a construction for a ballast which will enable the achievement of advantages described immediately above.

65 In prior attempts to decrease the size of the ballast, as by merely shortening the same, and making slight adjustments for the accommodation of the windings, it was found that the distance between the shunt and bridged gap was insufficient to give good operating characteristics. Magnetizing current increased requiring a heavier size of primary winding wire to carry the added primary current. 70 The space occupied by the primary winding was thus increased and necessitated a complete re-juggling of the

other dimensions which could not practically be done without added expense. A completely satisfactory design could not be achieved in this manner.

Another attempt was made in which the shunt projections were made longer than usual to decrease the size of the high reluctance gaps in the shunt. It was thought that this would decrease the magnetizing current, but it was found that too much flux was by-passed by the shunt giving rise to a lower open circuit voltage with consequent bad starting characteristics. Attempts to increase open circuit voltage would require more turns of wire on the secondary winding, which in turn would change operating characteristics, require changes in window dimension, etc. Furthermore, the metal removed from the bridged gap became excessive with this expedient.

Still another attempt involved punching the F-shaped and T-shaped laminations in a somewhat nested configuration but spaced lengthwise of one another, so that the displacement of the shunt from the bridged gap when the core was assembled was not the same as the width of the bridging ends. This produced a greater spacing between the shunt and bridged gap, but unfortunately it was found that the resulting increase in scrap offset the savings achieved by the resulting shorter ballast.

In accordance with the invention, the projections of the F-shaped laminations are formed with a narrow extension on their free ends, these extensions approaching the opposite side edges of the central winding leg and being spaced therefrom by a high reluctance air-gap of ordinary width. The notches thus removed from the T-shaped lamination are of identical configuration so that the bridged gap comprises a pair of aligned notches which are fairly wide but each having a narrow portion at its bottom end defining the narrow bridge therebetween.

Through the use of this type of structure, it was found that the laminations may be punched fully nested without any scrap; that the close proximity of the shunt and bridged gap did not result in any increase of magnetizing current; that the crest factor and lighting efficiency were excellent. It was found that the amount of copper wire needed was decreased; that the resulting ballast was constructed at a reduced cost; and that the ballast was quieter than heretofore.

Accordingly, other objects of the invention are to achieve the advantages mentioned by the structure described above.

The invention has been applied only to ballasts which are constructed by the method of Patent 2,892,249 and which are intended for use in circuits wherein the secondary winding carries a leading current, but it is believed that other ballasts for circuits of this same type may well use the invention with advantage, even though the laminations are not stamped as nested groups.

Other objects of the invention and advantages will become apparent to those skilled in this art as a preferred embodiment is described in some detail hereinafter, in connection with the drawings thereof.

In the said drawings:

FIG. 1 is a diagrammatic top plan view of a transformer constructed in accordance with the invention and using the novel core thereof, the coils of the apparatus being shown in section.

FIG. 2 is a fragmentary top plan view of a strip of electrical steel showing the layout of the parts of the core of FIG. 1 along the same in order to illustrate the manner in which the laminations are punched from the strip.

FIG. 3 is a view similar to that of FIG. 2 except in this case the strip of electrical steel is intended to pass through the punching machine in a direction at right angles to that of FIG. 2.

FIG. 4 is a circuit diagram of a ballast of the invention using the transformer of FIG. 1.

The invention herein is characterized by the provision of a ballast having a core that is formed by the method that is described in said Patent 2,892,249, but in which

the projections on the F-shaped laminations, which will eventually form the shunt, and the conforming notches on the T-shaped lamination, which will eventually aid in forming a bridged gap in the center winding leg, all have a narrow extension to achieve the results above described.

Furthermore, the invention is characterized by having the bridged gap formed at such a location along the length of the center winding leg so that it will occur under a secondary winding which carries a leading current. In addition to achieving the advantages of high lighting efficiency, low current and good regulation, such a construction provides flexibility of design and enables the manufacture of a highly efficient ballast having an overall length much less than heretofore.

The circuit diagram of the rapid-start lighting arrangement with which the invention is intended to be used is shown in FIG. 4. This circuit is conventional in all respects although the shunt and bridged gap resulting from the invention should be understood to be different from previous structures.

In said FIG. 4, there is a transformer 10 which is designated by straight lines indicating the conventional symbol for an iron core structure. The gap in the core structure at 12 indicates the bridged gap of the invention which will be described hereinafter, and the lines representing the shunt at 14 represent the shunt constructed in accordance with the invention. The core of the transformer will be designated 16.

There is a primary winding P which is connected across line terminals 18 and 20 by suitable leads marked black and white and indicating the preference respectively for the ungrounded and grounded line terminals. There is a secondary winding S which is mounted on the core 16 separated from the primary winding P by the shunt 14 but connected therewith at the terminal 22. A pair of fluorescent discharge lamps L₁ and L₂, preferably of the so-called rapid-start variety, are connected in series with one another by the jumper 24 and through the conductors 26 and 28 across both the primary and secondary windings. The conductor 26 extends to the junction 30 which is the left-hand terminal of the primary winding P, and the conductor 28 extends through the power factor condenser C_P to the right-hand terminal of the secondary winding S.

The circuit described is one in which the two lamps L₁ and L₂ are connected in series with one another and together in autotransformer connection with the primary and secondary windings. Each of the lamps L₁ and L₂ has a filament sealed in the respective envelope ends thereof as shown at F, and the filaments are served by continuous flow of current through the medium of filament windings F₁, F₂, and F₃ mounted on the core 16 closely coupled with the primary winding P and connected as shown. There is a shunting path 32 around the lamp L₂ which has a condenser C_S in said path.

The operation of this circuit is well known but may briefly be reviewed with advantage. On open circuit, the total open circuit voltage across the primary and secondary windings in additive relation appears across the lamp L₁ since the condenser C_S and C_P are not effective in circuit under open circuit conditions. The lamp L₂ is thereby shunted insofar as open circuit voltage is concerned.

The resulting voltage is sufficient to ignite the lamp L₁ and current immediately commences to flow therein. Since the lamp L₂ has not as yet been ignited, it presents a very high impedance to flow of current so that all of the current of lamp L₁ will prefer to pass through the condenser C_S. As soon as the by-pass path 32 has current flowing in it, a voltage is produced in the condenser C_S which appears across the lamp L₂ and is sufficient to ignite the lamp. Thereafter current prefers the lamp L₂ to the by-pass path 32, and the resulting operating circuit consists of the two lamps L₁ and L₂ in series with the power factor condenser C_P across the primary and secondary windings. The loose coupling between the

primary and secondary windings provides the leakage reactance to prevent excessive flow of current and keep the operating voltage to the desired level. The power factor condenser is needed so that the total power factor of the line 18 and 20 will be close to one hundred percent. Consequently, a leading current will flow in the secondary winding S.

FIG. 1 illustrates a transformer 10 constructed in accordance with the invention. The transformer 10 is formed of a laminated iron core 16 which has a center T-shaped part 40 and two side parts, each of which will be designated 42, of F-shaped configuration.

The type of transformer core with which this invention is concerned is that which is made of laminations punched from thin steel sheeting arranged in stacks and secured together. The individual laminations are of course identical for any given part, and hence, no effort will be made hereinafter to distinguish between the use of the reference numerals 40 and 42 to designate stacks or individual laminations of identical configuration.

The T-shaped part 40 provides the center winding leg 44 of the core 16 and its cross-head provides the left-hand bridging part 46. The F-shaped parts 42 provide the side legs 48 which are parallel with the center winding leg 44 and spaced therefrom to form windows at 50 and 52. The F-shaped parts have their left-hand or straight ends 54 butted against the cross-head or bridging part 46 at the joints 56 to close the magnetic circuit of the core 16 at the left-hand end thereof. The right-hand or inwardly projecting end 58 of the F-shaped parts 42 extend inwardly of the core 16 toward and about against the side edges of the free end of the center winding leg 44 at 60 to close the magnetic circuit thereat. The center inwardly extending projections 62 of the side legs 48 extend toward the center winding leg 44 and in cooperation with a high reluctance gap 64 formed thereat provide the shunt 14. The windings P, F₁, F₂, and F₃ are mounted in the window 52 and the winding S is mounted in the window 50.

It will be seen from the description above that the transformer 10 has its core 16 of the so-called shell variety with an outer rectangular framing portion and a center winding leg. The parts are formed of stacks of laminations as previously explained, and suitable notches 66 at the corners enable the core 16 to be held together by clamps symbolically illustrated at 68.

As previously mentioned, the laminations 40 and 42 are formed by the scrapless method of Patent 2,892,249. A strip of suitable steel is run through a punch press at high speed, and the individual laminations are punched out in nested configuration. A pair of F-shaped laminations 42 are nested on opposite sides of a T-shaped lamination so that the long inner edge of each of the F-shaped laminations is common with the long outer edge of the T-shaped lamination. Such groupings may be arranged edge to edge as shown in FIG. 2, then passed through the machine in the direction indicated by the arrow of FIG. 2. The only scrap which results will be the cross-hatched portions marked S which, it will be noted, include punch-outs for the notches 66. In addition, there may be a narrow holding strip on opposite edges of the wide metal strip in accordance with normal high-speed punch press techniques.

The orientation of the steel grain can be made parallel with the long dimension of the laminations by arranging the groupings of a pair of F-shaped laminations 42 and their inter-nested T-shaped laminations 40 end to end along a narrow strip as shown in FIG. 3 and passing this strip through the punching machine in the direction as shown by the arrow to give rise to the scrap parts shown. A holding strip may also be required along the edges of the strip of FIG. 3.

It will be appreciated that in arriving at the assembly of the core 16 from a grouping such as shown in either FIG. 2 or FIG. 3, the F-shaped parts are first moved

sideways away from the T-shaped part and then translated lengthwise thereof to the orientation shown. Consequently, for a complete absence of scrap at the points designated A and B, in FIG. 2, for example, it is essential that the dimensions X, Y and Z in FIG. 1 be equal.

When the core 16 is formed, there will be a notch 70 in each edge of the center winding leg 44, thereby giving rise to the so-called bridged gap 12. The bridging part is designated 72, and the amount of saturation in the center winding leg 44 which can be tolerated so that the current flowing in the secondary winding S has the best crest factor normally is controlled by the relative size of the bridging portion 72 and the remainder of the bridged gap 12. Likewise, the characteristics of the ballast in operation will be affected by the distance between the shunt 14 and the bridged gap 12.

As previously mentioned, through the medium of the invention, a ballast previously manufactured and sold was considerably decreased in size with attendant savings and improvement in operation. In accordance with the invention, each of the inward projections 62 of the side legs 48 is provided with a narrow end extension 74, and resulting in a narrow recess 76 being formed at the bottom of each of the notches 70. Through this construction, the optimum bridge 72 readily may be established and the width of the extensions 74 adjusted along with the gaps 64 for optimum crest factor, magnetizing current, and lighting efficiency.

As previously indicated, in the prior structure where projections 62 were made very long in order to bring them close to the edge of the center winding leg, the resulting notches at 70 would be so deep as to leave insufficient iron at the bridging center 72 to carry normal flux. This would reduce the light output through peaking of the current wave. When the extensions 74 with their resulting recesses 76 are used, there appeared to be no difficulty through distortion. It is believed that sufficient flux passed through the recesses 76 to give a good current wave shape.

With this structure, therefore, the configuration of the shunt could be used to achieve lower magnetizing current and lower primary current. A fair gap and the extensions 74 kept reluctance high enough to give good open circuit characteristics. It was found that the structure was quieter than the previous structure, probably caused by bypassing more flux at peak voltage wave.

A practical example of a ballast for operating two rapid-start fluorescent lamps will be described below, but in order to show the specific advantages of the invention, a comparison will be made with the previous structure. It will first be pointed out that the same capacitors C_S and C_{PF} were used, these being .05 m.f.d. and 3.83 m.f.d., respectively with a 385 volts A.C. rating; the lamps were the same, requiring about 430 milliamperes of current, igniting at about 260 volts, and operating at about 105 volts. Live voltage was 120 volts A.C. at 60 cycles. Lamp current was .400 ampere with a crest factor of 1.35. Primary current was the same for both ballasts.

60 Ballasts for two 40-watt rapid-start fluorescent lamps

	Item or characteristic	Previous Structure	Present Structure
65	Overall length of core 16.....inches	4.25	3.74

	Bridging distance 72.....do	.40	.290
	Gap 64.....do	.085	.040
	Window Width.....do	.310	.320
70	Primary winding #26 gauge wire.....turns	799	745
	Secondary winding #27½ gauge wire.....do	1,455	1,340
	Filament windings #26 gauge wire.....do	26-29	25-28
	Primary current.....ampères	.620	.580
	Crest factor.....	1.35	1.35

As indicated above, the structure of the invention has

been applied practically to ballasts for operating two 40 watt rapid start fluorescent lamps, but there is no reason why the advantages of the invention should not be achieved in rapid-start or the like circuits of different kinds using one or more such lamps. Furthermore, although most of the benefits are provided when the laminations are stamped by scrapless methods, it is believed that the use of shunting projections with narrow extensions combined with a bridged gap under a secondary winding carrying a leading current is new, especially where the gap is formed by means of what might be termed notches of non-uniform width.

Accordingly, notwithstanding the somewhat specific detail in the description hereinabove, it should be appreciated that variations are possible without departing from the spirit or scope of the invention as defined in the appended claims.

What is desired to secure by Letters Patent of the United States is:

1. A ballast structure for igniting and operating at least one gaseous discharge device from an alternating current source, and which comprises a transformer having a core made up of laminations of nested configurations, but re-arranged to provide a center T-shaped part formed of one stack of laminations and two outer F-shaped parts formed of two additional stacks of laminations, but with the long legs of the parts spaced to provide winding windows, a pair of lateral projections one in the center of each F-shaped part extending across the space toward the long leg of the T-shaped part but each projection having its free end terminating short of said long leg of the T-shaped part to form gaps thereby and provide a shunt, said free ends being of substantially lesser width than the respective projections to form narrow extensions at said gaps respectively, primary and secondary windings in transformer relation mounted on the long leg of the T-shaped part and disposed in windows on opposite sides respectively of said shunt, a condenser, first lead means for connecting the primary winding across the source and second lead means for connecting at least the secondary winding in series with the condenser and the discharge device, a notch in each edge of the long leg of the T-shaped part under the secondary winding and adjacent each projection, of a configuration and of dimensions substantially the same as the configuration and dimensions of said adjacent projection.

2. A structure as claimed in claim 1 in which the primary and secondary windings are connected in auto-transformer relationship.

3. A structure as claimed in claim 1 in which every point on each projection is spaced from the equivalent point on its adjacent notch by a distance measured along the length of the long leg of the T-shaped part which is substantially equal to the width of the cross-head of said T-shaped part.

4. In a ballast construction for operating at least one gaseous discharge device from an alternating current source, in which there is a transformer having a shell type core mounting a primary winding and a secondary wind-

ing, there being a shunt between the windings and a bridged gap beneath the secondary winding, the core being formed of a center T-shaped part and a pair of inwardly facing outer F-shaped parts, the shunt being provided by the center projections of the F-shaped parts extending toward the center T-shaped part but stopping short thereof to form gaps thereat, the bridged gap being provided by notches in the side edges of the center T-shaped part, and in which the windings are connected with the gaseous discharge device and a condenser so that there is a leading current adapted to flow in the secondary winding during operation of the gaseous discharge device; the herein invention which comprises: the free ends of the projections being substantially narrower than the remainder of the projections forming flux-confining extensions on said projections immediately adjacent the respective shunt gaps.

5. The invention as claimed in claim 4 in which the notches are of irregular configuration being of smallest width at their inner ends.

6. The invention as claimed in claim 4 in which the notches and projections including the extensions thereof are of the same dimensions and configurations.

7. A fluorescent lamp ballast for igniting and operating at least a pair of lamps from an alternating current source, said lamps being connected in series, said ballast including a transformer having a shell type core formed of a T-shaped center leg and F-shaped side legs, a primary winding and a secondary winding mounted on the center leg and separated by a shunt, the center projections of the F-shaped parts extending toward the center leg to provide said shunt and being slightly spaced therefrom to provide the gaps of the shunt, the windings being connected in auto-transformer relation to said lamps, a power factor correcting condenser in series with the secondary winding and effective during operation of the ballast to cause a leading current to flow in said secondary winding, a bridged gap in the center leg beneath the secondary winding, said gap being provided by notches cutting into the center winding leg from opposite edges thereof, the notches each having an inner-most recess the width of which is substantially less than the remainder of the notch, thereby reducing the amount of iron in the bridge but the width of the recesses being such as to permit some passage of flux during operation to prevent undue saturation of the bridge.

8. A structure as claimed in claim 7 in which the center projections have a configuration and dimensions substantially the same as the notches to provide extension tips on the ends thereof adjacent the gaps, respectively.
